UNITED STATES PATENT OFFICE.

CLYDE AUNGER, OF SAN FRANCISCO, CALIFORNIA.

ARTIFICIAL HAND.

1,193,969.

Specification of Letters Patent.

Patented Aug. 8, 1916.

Application filed August 23, 1915. Serial No. 47,902.

To all whom it may concern:

Be it known that I, CLYDE AUNGER, a citizen of the United States, residing in the city and county of San Francisco and 5 State of California, have invented a certain new and useful Improvement in Artificial Hands, of which the following is a specification.

My invention relates to artificial hands 10 wherein separable hooks matching with each other, are adapted to be partially rotated when the elbow is bent so as to bring the hooks or an article held therein into proper position when the arm or hand is 15 raised toward the mouth or head.

The present state of the art discloses various forms of artificial arms having movable fingers and rotatable hands thereon but it has been found from experience that the 20 movable fingers are not convenient for picking up and holding table utensils, tools and the like and moreover are easily broken in lifting heavy objects. Persons who have had their arms amputated grow accustomed 25 to the conspicuousness of their loss to such an extent that a serviceable device is preferred to one less convenient with a better appearance.

The object therefore of this invention, is 30 to provide a convenient and efficient device which is capable of the greatest number of uses and at the same time simple of construction and operation as well as cheap and light in weight.

35 A stationary hook, while it answers the purpose of lifting and conveying heavy objects, is not adapted for eating, brushing the hair or teeth, removing or replacing the hat and such objects, for the reason that an 40 object such as a knife and fork, tooth brush, comb or the like, would not be in proper position when the elbow of the wearer of the said hook was bent, but would extend from the stationary hook away from the head or 45 mouth.

I propose to provide an improved artificial hand which is adapted for various uses, may be quickly and easily opened and closed and partially rotated by the natural bending of the elbow so as to simulate the turning movement of the wrist as in raising food to the mouth.

50 I accomplish these features by means of the device disclosed in the drawings forming a part of the present specification, wherein like characters of reference are used

to designate similar parts throughout the said specification and drawings, and in which—

Figure 1 is a broken vertical sectional view of the end of a socket adapted to be fastened to the stump of an amputated arm, disclosing the manner in which the several parts are arranged. Fig. 2 is a bottom view of the metallic cup removed from the end of 65 the socket. Fig. 3 is a top view of the metallic cup with the hooks removed, and Fig. 4 is a view of the socket attached to the amputated arm.

Referring to the drawings, the numeral 1 70 is used to designate a socket adapted to be fastened to the stump of an amputated arm and having a metallic cup 2 secured to the end thereof. The metallic cup 2 has a tubular extension 3 formed integral therewith 75 within which is rotatably mounted the sleeve 4 of a plate 6, said sleeve 4 and plate 6 having a longitudinal squared aperture 7 therethrough. A hook 8 is provided with a square shank 9 adapted to engage the 80 squared aperture 7, and having a reduced cylindrical groove 11 therein, adapted to be engaged by a suitable latch 12 slidably mounted upon the plate 6 and having a central slot therein comprising a circular portion 14 adapted to engage the reduced cylindrical portion or groove 11 of the square shank 9 of the hook 8 and thereby retain said hook 8, and a substantially square portion 16 85 adapted to permit the passage of the said shank 9. A suitable spring 17 is arranged to normally retain the circular portion 14 over the end of the squared aperture 7 in the plate 6. A suitable pin 18 is secured to one end of the latch 12 and extends through 90 a slot 19 in the plate 6 and an arcuate slot 21 having a lateral extension 22 therein, in the metallic cup 2, the purpose of which will hereinafter be more fully described.

The socket 1 has metallic side bars 23 secured to one end thereof, and pivotally mounted upon similar metallic side bars 24 secured to a fastening means 26 adapted to be fastened to the arm above the elbow. The metallic side bars 24 have an arcuate extension 27 connecting the ends thereof and passing around the elbow of the wearer. A cord 28 has one end secured to the extension 27 at a point directly back of the elbow and the other end thereof extends along the back 110 of the socket 1 and through an aperture 29, therein, and after passing over a suitable

pulley 31 is secured to a pin 32 in the plate 6 so that when the elbow is bent to raise the socket 1 the said cord 28 will pull upon the pin 32 and partially rotate the said plate 6 and the hook 8 detachably secured thereto. When the arm is extended or returned to a substantially straight position a suitable spring 33, secured to the plate 6 and to the inner surface of the metallic cup 2, normally returns or rotates the plate 6 and the hook 8 to a normal position.

While the plate 6 and hook 8 detachably secured thereto are rotating, the pin 18 traverses the arcuate slot 21 thereby locking the latch 12 and preventing the hook 8 from being inadvertently detached from the plate 6 while the hook 8 is carrying an article, as the said hook can only be detached from the plate 6 by moving the pin 18 into the extension 22 of the slot 21 thereby causing the square portion 16 of the slot within said latch 12, to coincide with the end of the square aperture 7 when the square shank 9 of the hook may be withdrawn.

A second hook 36 is provided with an arm 37 and is pivotally mounted upon the hook 8 as at 38. The hook 36 is adapted to match with the hook 8 and to normally close thereon by means of a suitable spring 39.

A cord 41 has one end thereof secured to the end of the arm 37 and after passing through a suitable aperture 42 in the metallic cup 2 and a suitable aperture 43 near the end of the socket 1, also passes through a suitable guide 43 secured to the metallic side bars 23 and has its other end fastened or secured to a shoulder piece 44. The hook 36 is also provided with an extension 46 against which an article secured between the hooks 8 and 36 may be held and thereby further supported.

The device may be operated as follows: A certain pressure of certain shoulder muscles on the part of the wearer will tend to tighten the cord 41 which is also connected to the arm 37 of the hook 36 and cause the separation of the hooks 36 and 8 for the purpose of grasping an article. When said pressure is released the spring 39 will close the hooks 8 and 36 upon each other and thereby firmly grasp the article. If the article grasped should be a fork containing food to be carried to the mouth of the wearer, the hooks 8 and 36 will be partially rotated substantially through an arc of 90 degrees thereby bringing the food into a position where it may be easily received by the mouth by the natural bending of the elbow which will pull upon the cord 28 and thereby rotate the plate 6 and the hooks 8 and 36 secured thereto, as hereinbefore described. In transporting or carrying heavy articles such as suit cases, satchels and the like, the handle of the said article may be secured by the hooks 8 and 36. The hooks

8 and 36 will be effectively secured against detachment by means of the circular portion 14 of the latch 12 which engages the cylindrical groove 11 on the shank 9 of the hook 8.

From the foregoing it is obvious that I have provided an improved artificial hand adapted for various uses and also improved means for partially and automatically rotating the said hand by a natural bending of the elbow. I have also provided an improved artificial hand which is simple, cheap and durable in construction as well as in operation.

I am aware that the present state of the art discloses matching hooks adapted to be separated by a certain pressure of certain shoulder muscles, therefore I do not wish to claim such a combination broadly as my invention but—

What I do claim and desire to secure by Letters Patent is—

1. An artificial hand comprising a socket adapted to be fastened onto the stump of an amputated arm; a hook detachably and rotatably mounted in and extending beyond the end of the socket; a second hook pivotally mounted upon the first mentioned hook and arranged to form a gripping means therewith; fastening means pivotally connected to the socket and adapted to be fastened to the arm above the elbow; and means operatively connected to the hooks and to the fastening means whereby said hooks may be partially rotated when the arm of the wearer is bent.

2. An artificial hand comprising a socket adapted to be fastened to the stump of an amputated arm; a plate rotatably mounted within the end of the socket; a hook detachably secured to the plate; a second hook pivotally mounted upon the first mentioned hook and arranged to form a gripping element therewith; fastening means pivotally connected to the socket and arranged to be secured to the arm above the elbow; means operatively connected to the hooks and to the fastening means whereby the said hooks may be partially rotated when the elbow of the wearer is bent; and means operatively connected to the plate and adapted to detachably secure the first mentioned hook thereto.

3. An artificial hand comprising a socket adapted to be fastened to the stump of an amputated arm; a plate rotatably mounted within the end of a socket; a hook detachably secured to the plate; a second hook pivotally mounted upon the first mentioned hook and arranged to form a gripping element therewith; fastening means pivotally connected to the socket and arranged to be secured to the arm above the elbow; means operatively connected to the hooks and to the fastening means whereby the said hooks

may be partially rotated when the elbow of the wearer is bent; means operatively connected to the plate and adapted to detachably secure the first mentioned hook; and

5 means operatively connected to the socket and to the plate and adapted to normally return said plate and the hooks detachably secured thereto to a normal position when the elbow and arm of the wearer is straightened.

10 4. An artificial hand comprising a socket adapted to be secured to the stump of an amputated arm; fastening means pivotally connected to the socket and adapted to secure the same to the arm; a plate rotatably mounted within the end of the socket; a hook detachably secured to the plate; a second hook having an arm thereon and pivotally mounted upon the first mentioned

15 hook and matching therewith; a suitable spring adapted to normally close the hooks together; a cord fastened to the arm of the second mentioned hook and to the shoulder of the wearer whereby the hooks may be separated; a second cord secured to the rotatable plate and to the fastening means of the socket and adapted to partially rotate the hooks when the elbow is bent; and means adapted to return the plate and hooks se-

20 30 cured thereto to a normal position when the arm is extended.

5. An artificial hand comprising a socket adapted to be secured to the stump of an amputated arm; fastening means pivotally connected to the socket and adapted to secure the same to the arm; a plate rotatably mounted within the end of the socket; a hook detachably secured to the plate; a second hook having an arm thereon and pivotally mounted upon the first mentioned hook and matching therewith; a suitable spring adapted to normally close the hooks together; a cord fastened to the arm of the second mentioned hook and to the shoulder of the wearer whereby the hooks may be separated; a second cord secured to the rotatable plate and to the fastening means of the socket and adapted to partially rotate the hooks when the elbow is bent; and a suitable spring operatively connected to the rotatable plate and to the socket and adapted to normally retain the said plate in a normal position.

6. An artificial hand comprising a socket adapted to be fastened to the stump of an amputated arm; fastening means pivotally

connected to the socket and adapted to fasten the same to an arm; a metallic cup rigidly secured to the end of the socket and having a tubular extension thereto; a plate having 60 a sleeve rotatably mounted within the tubular extension and a squared longitudinal aperture through said sleeve and plate; a hook having a square shank mounted within the squared aperture; means adapted to detachably secure the square shank within the said aperture; a second hook having an arm thereon and pivotally mounted upon the first mentioned hook and matching therewith; a suitable spring adapted to normally close the 65 hooks; a cord secured to the arm on the second hook and to shoulder of the wearer whereby the hooks may be separated; a second cord secured to the rotatable plate and to the fastening means of the socket and 70 adapted to partially rotate the said plate and the hooks when the elbow is bent; and a suitable spring adapted to normally return the plate and hooks thereon to a normal position when the arm is extended.

7. An artificial hand comprising a socket adapted to be fastened to the stump of an amputated arm; fastening means pivotally connected to the socket and adapted to fasten the same to an arm; a metallic cup 85 rigidly secured to the end of the socket and having a tubular extension thereto; a plate having a sleeve rotatably mounted within the tubular extension and a squared longitudinal aperture through said sleeve and 90 plate; a hook having a square shank mounted within the squared aperture; a suitable latch adapted to detachably secure the square shank within the said aperture; a second hook having an arm thereon and 95 pivotally mounted upon and matching with the first mentioned hook; a suitable spring adapted to normally close the hooks; a cord secured to the arm on the second hook and to the shoulder of the wearer whereby the 100 hooks may be separated; a second cord secured to the rotatable plate and to the fastening means of the socket and adapted to partially rotate the said plate and the hooks when the elbow is bent; and a suitable spring 105 adapted to normally return the plate and hooks thereon to a normal position when the arm is extended.

In witness whereof I hereunto set my signature.

CLYDE AUNGER.
